Sherman Dewey Beckley, Sedalia, Mo.

Application February 9, 1954, Serial No. 28,925

Term of patent 14 years

(Cl. D54—16)

To all whom it may concern:

Be it known that I, Sherman Dewey Beckley, a citizen of the United States, and a resident of Sedalia, county of Pettis, State of Missouri, have invented a new, original, and ornamental Design for a Multiple-Head Barrel Wrench, of which the following is a specification, reference being had to the accompanying drawings, forming a part thereof, in which:

Figure 1 is a top plan view of a multiple-head barrel wrench, embodying my new design;

Figure 2 is a side elevational view thereof;

Figure 3 is a cross-sectional view taken on line 3—3 of Figure 1;

Figure 4 is a cross-sectional view taken on line 4—4 of Figure 1; and

Figures 5 through 9, inclusive, are fragmentary side

elevational views looking in the directions of the arrows 5 through 9, respectively, of Figure 1.

I claim:

The ornamental design for a multiple-head barrel wrench, substantially as shown.
